United States Patent Office

Des. 197,174
Patented Dec. 24, 1963

197,174

HOUSING UNIT

Oliver D. Filley, Jr., Bedminster, N.J., assignor to Black River Pool & Plastics, Inc., Sommerville, N.J., a corporation of New Jersey

Filed June 3, 1963, Ser. No. 75,194

Term of patent 14 years

(Cl. D13—1)

FIG.1

FIG.4

FIG. 1 is a perspective view of the housing unit seen from the front and right side thereof showing my new design;

FIG. 2 is a front view of the unit;

FIG. 3 is the left side view of the unit;

FIG. 4 is a rear view of the unit; and

FIG. 5 is a top view of the unit.

I claim:

The ornamental design for a housing unit, substantially as shown.
